Primary Examiner — Mark T. Philippss(74) *Attorney, Agent, or Firm* — Olive Law Group, PLLC(57) **CLAIM**

The ornamental design for an intelligent inflator pump, as shown and described.

DESCRIPTION

FIG. 1 is a bottom, front and right side perspective view of an intelligent inflator pump showing my new design; FIG. 2 is a top, rear and left side perspective view thereof; FIG. 3 is a front elevational view thereof; FIG. 4 is a rear elevational view thereof; FIG. 5 is a left side elevational view thereof; FIG. 6 is a right side elevational view thereof; FIG. 7 is a top plan view thereof; FIG. 8 is a bottom plan view thereof; FIG. 9 is an enlarged view of the portion 9 in FIG. 1; and, FIG. 10 is an enlarged view of the portion 10 in FIG. 2. The evenly dashed broken lines illustrate portions of the intelligent inflator pump. The unevenly dashed broken lines define the boundaries of the enlarged view. None of broken lines form part of the claimed design.
